UNITED STATES PATENT OFFICE.

PETER R. GOTTSSTEIN, OF HOUGHTON, MICHIGAN.

CANDLE-MOLDING MACHINE.

SPECIFICATION forming part of Letters Patent No. 242,630, dated June 7, 1881.

Application filed April 11, 1881. (No model.)

To all whom it may concern:

Be it known that I, PETER R. GOTTSSTEIN, of Houghton, in the county of Houghton and State of Michigan, have invented a new and 5 useful Improvement in Candle-Molding Machines, of which the following is a specification.

Figure 1 is a perspective view of my improved candle-molding machine. Fig. 2 is a 10 sectional view of a portion of the machine, taken vertically through the center of one of the molds. Fig. 3 is a view of the upper end of one of the hooked needles O.

My invention consists, first, in a machine for 15 molding candles, having hooked needles passing through the pistons and molds, by which the wicks are drawn through the molds and so held that when the candles are molded the wicks will project from the candles in the form 20 of loops; second, in a bar or bars running across the top of a candle-molding machine and having a hole over the center of each mold through which the wick passes and is held in position in the center of the mold.

Referring to the drawings, the letter A is the 25 frame of the machine, in which K are molds, L are pistons with a tip-mold, M, at the upper end thereof, C is a board, to which the lower ends of the pistons are fastened, F F 30 are racks attached to board C, and E E are pinions working in racks F F, by which board C, with pistons L, can be raised and lowered.

The above-described part of my improved 35 candle-machine is similar to the well-known Stainthorp candle-molding machine.

D is a board placed below board C. H H 40 are racks fastened to board D, and engaging with pinions G G fastened to board C. It will be seen that when board C is raised by pinions E and racks F it will also raise board D, and that board D can also be raised independent of board C by pinions G and racks H.

O are wire needles, formed with a hook, P, 45 Fig. 3, at the upper end, and flattened or grooved above the hook. The distance from the end of the needle to the hook determines the length of the loop which will be formed in the wick, and may be any distance desired. As is shown in Fig. 2, the mold K and its accompanying 50 piston L and needle O are concentric, the needle O passing through a hole in the center of the piston.

J is a frame resting on top of frame A.

I I are metal bars passing across frame J and running over each series of molds K. Over 55 the center of each mold a small hole, R, is made in bar I, large enough to allow needle O when raised to pass through bar I until hook P stands above bar I.

It is obvious that bars I I may be placed directly on the top of frame A without being fastened in a separate frame.

The wicking is cut on a machine, or by hand, into lengths of twice the length of the candle, plus the loop to project from the candle. The 65 wicks are then doubled and the loose ends are dipped into hot grease, so as to form a lump of grease on the end of the wick.

The operation of the machine is as follows: The bars I I are laid across the frame A, and, 70 by means of pinions E E and G G, and racks F F and H H, boards C and D are raised until the hooks P of needles O stand above bars I I. The wicks are then slipped into hooks P, and boards C and D are lowered until the tops 75 of needles O stand at the bottoms of tip-molds M, and tip-molds M are at the bottoms of molds K. The material of which the candles are to be made is then poured into molds K. As needles O are lowered the wicks are drawn 80 through holes R in bars I I, and are kept from falling into the molds K by the lump of grease on the end of each wick, which is made too large to pass readily through hole R in bar I. When the candles are sufficiently hard they 85 are forced out of the molds K by raising pistons L in the ordinary manner, above described, first removing bars I I, and by raising needles O, as above described, until the wicks can be unhooked from them.

Any of the racks in common use can be used 90 to receive the candles when pushed out of the molds.

What I claim as my invention, and desire to 95 secure by Letters Patent, is—

1. In a candle-molding machine, the combination, with the frame A, having molds K and pistons L, fastened to board C, so that said pistons can be raised and lowered at will, of the board D, so hung to board C that it will rise and fall therewith, but capable of being raised and lowered independent thereof, and hooked needles O, fastened to board D and running through the center of pistons L, all

constructed, arranged, and operating substantially as herein shown and described.

2. In a candle-molding machine, the combination of the molds K, pistons L, and hooked needles O, having suitable mechanism for raising and lowering said pistons and hooked needles simultaneously, and for raising and lowering said hooked needles independently, with the bars I, having holes R therein, substantially as and for the purposes described. 15

3. In a candle-molding machine, the combination of the frame A, bars I, molds K, pistons L, having tip-molds M, board C, hooked needles O, board D, pinions E and G, and racks F and H, substantially as shown and described. 15

PETER R. GOTTSSTEIN.
